LET-OFF FOR LOOMS

Application filed March 21, 1928. Serial No. 263,471.

This invention relates to improvements in let-offs for looms and it is the general object of the invention to provide means for rendering inoperative a portion of the mechanism so that the operator may more conveniently manipulate the warp beam.

In many looms the resistance offered to the forward movement of a warp beam is supplied by a pair of friction devices, one

10 at each end of the beam. It is not unusual to supply two weighted levers with chains, ropes or cables extending over the drums on the ends of the beam. At the time of pick-out after a mispick the weaver will ordinarily be called upon to move the beam backwardly an amount sufficient to take-up the warp remaining in advance of the reed after the pick-out. This operation is ordinarily accomplished by hand but both levers

20 must be raised to relieve the friction before the beam can be reversed. It is an important object of our present invention to provide one of the levers with a spring plunger which is normally in retracted position but which may be released so as to cooperate with holding structure to sustain one of the levers in friction releasing position, thereby permitting the weaver to raise the other lever with one hand and manipulate the

30 beam with the other hand. After the beam has been moved back sufficiently the lever under control of the weaver may then be depressed to hold the beam in its new position, after which the weaver may take her hand from the beam and relieve the plunger so that the lever formerly inactive may return to position to exert friction on the beam head.

It is a more specific object of our present 40 invention to provide a plunger on the let-off lever which is designed to register with an opening formed in one of the cross girts of the loom.

In one form of let-off which has gone 45 into general use there are mounted on the weighted lever two independently movable devices which, however, are normally locked together by means of a hold pawl. One of these devices is connected to the free end of a chain or cable which exerts fric-

tion on the adjacent end of the warp beam and the other device is held by means of a set screw fixed in angular position on the weighted lever. Such a construction facilitates adjustment of the lever relatively to the chain so that the lever may be lowered sufficiently so that the opening in the cross girt will come within the range of movement of the plunger.

With these and other objects in view which will appear as the description proceeds, our invention resides in the combination and arrangement of parts hereinafter described and set forth in the claims.

In the accompanying drawings, wherein we have shown a convenient embodiment of our invention,

Fig. 1 is a rear elevation of a loom having our invention applied thereto,

Fig. 2 is an enlarged plan view taken in the direction of arrow 2, Fig. 1, and showing the plunger in inactive position,

Fig. 3 is a view similar to Fig. 2 but with the plunger moved to operative position to sustain one of the levers in a position where the friction element associated therewith is relieved,

Fig. 4 is a vertical section on line 4—4 of Fig. 2, and

Fig. 5 is a vertical section on line 5—5 of Fig. 2.

Referring particularly to Fig. 1, the loom frame 10 supports a warp beam W provided with gudgeons 11 which are supported by the frame. A cross girt 12 extends between the opposite sides of the frame and may be held in fixed position by means of bolts 13. Secured to each end of the girt 12 is a bracket 14 having a rearwardly extending substantially horizontal stud 15 on which is pivoted the hub 16 of a weighted lever 17. Each lever is provided with notches 18 to receive a hooked end 19 of a weighted element 20, each element being movable along its lever to assume different distances from the corresponding stud 15. Each end of the warp beam is provided with a drum 21 around which extends a flexible friction element 22 which may be a rope, cable, chain, strap or other suitable device. Each end

of the girt 12 is provided with a clip 23 which receives one end of the corresponding cable or flexible element 22 to hold said end in fixed position.

The other or free end of each cable, after being wrapped around the associated drum, is held by means of a hook 24 to a disk 25 by extending through an opening 26 formed in the latter as set forth in Fig. 4. There are two disks, one for each lever, and each disk has cast integral therewith a hub 27 and a ratchet 28. Each hub is free to turn on the substantially cylindrical portion 29 of the corresponding lever 17. A second member 30 is held to the lever 17 by means of a set screw 31 and there is pivotally mounted on said member 30 a pawl 32 which normally has holding engagement with one or another of the teeth of the ratchet 28. Said pawl extends upwardly through an opening 33 in the member 30 and projects sufficiently far to be readily accessible to the upper end. By means of the pawl and ratchet the disk 25 and member 30 are held in fixed angular position when the flexible element 22 is taut. When it is desired to change the vertical position of the lever 17 the pawl 32 may be moved out of the holding position after which the disk 25 may be turned in the correct direction to produce the desired movement on the part of the lever 17. The pawl 32 may then be inserted in one of the teeth of the ratchet to hold the new position of the lever. It is to be understood that each side of the loom is provided with a lever 17 and associated devices. The particular form of connection between the chain or flexible element 22 and the lever 17 has been in common use for a number of years and forms no part of our present invention.

As previously stated it is desirable to be able to reverse the warp beam at time of a mispick, but such an operation requires the movement of three separate devices, namely, the beam W, and both levers 17. Such an operation is obviously inconvenient as the weaver has only two hands with which to perform the operation and our invention relates particularly to means for holding one of the levers 17 in raised position, thereby relieving the friction corresponding thereto and simplifying the beam reversing operation. Accordingly, in carrying our invention into effect, we provide one of the levers 17 with a plunger 40 having a pin 41 between which and the lever is located a compression spring 42 which tends to move said plunger toward the girt 12. The plunger extends through a portion of the lever 17 as shown in Fig. 2 and the rear end thereof is bent laterally as at 43 and extends into alignment with a portion of the member 30 which may be notched as at 44 to receive said offset. The girt 12 may be provided with an opening 45 which is so located that

the lever 17 may be moved to cause registry of said opening with the plunger 40.

Under normal operations the lever 17 which carries the plunger 40, that is the left hand lever as shown in Fig. 1, will be so disposed by the adjustment of the disk 25 and the member 30 through the pawl and ratchet that the plunger 40 will be located below the opening 45. When a pickout operation requires the reversing of the warp beam W the weaver will move the lever to the dotted line position shown in Fig. 1 and will also rotate the plunger 40 sufficiently to free the offset end 43, thereby permitting said plunger to move toward the girt 12. By properly positioning the lever 17 the forward end of the plunger will pass into the opening 45 so as to sustain the lever 17. This produces a slackening of the flexible element 22 on the left hand side of the loom and the weaver may then raise the other lever 17 with the right hand and pull the warp beam back with her left hand. When the beam has assumed the proper position the right hand lever 17 may be depressed to clamp it to the right hand side of the beam through the adjacent flexible element thus freeing the weaver's left hand which may then withdraw the plunger 40 to release the left hand lever 17.

From the foregoing it will be seen that we have provided a very simple means for assisting the weaver in reversing the warp beam after a pickout operation by providing a plunger effective to hold one of the levers 17 in a position which will slacken the corresponding friction element, thereby freeing one of the weaver's hands for reversing the warp beam. It will further be seen that because of the relative adjustment between the disk 25 and the member 30 it is possible to keep the lever 17 which carries the plunger 40 in such a position that the latter is normally below the opening 45. While we have shown an opening 45 yet we find that when the warp beam is sufficiently small in diameter the plunger may extend over the top of the girt 12.

Having thus described our invention it will be apparent that changes and modifications may be made therein by those skilled in the art without departing from the spirit and scope of the invention and we do not wish to be limited to the details herein disclosed, but what we claim is:

1. In a let-off for a loom having a frame, a warp beam and a lever pivotally mounted with respect to the frame, connections between the lever and the beam whereby the lever acts when in normal position to retard movement of the beam, a manually operative spring actuated device normally held in inactive position and supported by the lever and movable therewith, said device tending to move toward active position to

have engagement with the frame to hold said lever in abnormal position to render the connections ineffective to retard movement of the beam.

5 2. In a let-off for a loom having a frame, a warp beam and a lever pivotally mounted with respect to the frame, connections between the lever and the beam whereby the lever acts when in normal position to retard movement of the beam, a spring plunger slidably mounted in the lever, means to hold said plunger in inactive retracted position out of the path of the frame, said plunger being movable relatively to the lever to have 70 engagement with a portion of the frame to hold said lever in abnormal position to render the same ineffective to retard movement of the beam.

3. In a let-off for a loom having a frame 20 and a warp beam, a lever pivotally mounted with respect to the frame, connections between the lever and the beam whereby the lever acts when in normal position to retard movement of the beam, a plunger mounted 85 in said lever for sliding and angular movement relatively to said lever, said plunger when in a given angular position being restrained against movement toward the frame and said plunger when in another angular 90 position relatively to the lever being movable into holding engagement with respect to the frame of the loom to hold the lever in such a position as to render the same ineffective to retard movement of the beam.

35 4. In a let-off for a loom having a frame and a warp beam, a lever pivotally mounted with respect to the frame, connections between the lever and the beam whereby the lever acts when in normal position to retard movement of the beam, a plunger mounted 100 in the lever for angular and sliding movement relatively to the lever, a member carried by the lever having engagement with the connections, a retaining element rigid 105 with the plunger and normally in engagement with the member to hold said plunger out of engagement with the frame, said plunger being movable angularly with respect to the lever to move the element 110 away from the member, the plunger thereafter being movable into engagement with the frame to hold the lever in a position to be ineffective to retard movement of the beam, and a spring tending normally to 115 move the plunger into engagement with the frame of the loom.

5. In a let-off for a loom having a frame and a warp beam, a lever pivotally mounted with respect to the frame, connections between the lever and the beam whereby the lever acts when in normal position to retard movement of the beam, an element mounted 120 in the lever and capable of assuming a plurality of rotative positions relatively to the lever, said element being attached to the 125

connections whereby angular movement of said element is accompanied by a change in the relation of the connections with respect to the lever, and means carried by the lever to have engagement with the frame to hold said lever in position to be ineffective to retard movement of the beam.

6. In a let-off for a loom having a frame, a warp beam and a lever pivotally mounted with respect to the frame, a member rotatable on the lever and having operative connection with the beam, said member being normally fixed relatively to the lever and having a depression therein, a sliding and rotative element mounted in the lever, and a resilient device operatively connected to the element and tending to move the element toward the frame and tending also to hold a portion of the movable element in the depression, whereby the movable element is normally held in inactive position, said lever being held by the movable element in a position to be ineffective to retard movement of the beam.

In testimony whereof we have hereunto affixed our signatures.
